UNITED STATES PATENT OFFICE.

JACOB FALKENBERG, OF NEW YORK, N. Y.

SAFETY CUFF-BUTTON SHIRT.

1,100,674.

Specification of Letters Patent. Patented June 16, 1914.

Application filed August 12, 1913. Serial No. 784,289.

To all whom it may concern:

Be it known that I, JACOB FALKENBERG, a citizen of the United States, and a resident of the city of New York, borough of Manhattan, in the county and State of New York, have invented a new and Improved Safety Cuff-Button Shirt, of which the following is a full, clear, and exact description.

This invention relates to garments and has particular reference to men's shirts of the soft variety.

The primary object of this invention is to avoid the common objection to soft shirts with respect to the loss of valuable cuff buttons.

The main object, therefore, of the invention is to devise a safety attachment for a soft shirt cuff which has constant coöperation with the shank of the button and will prevent the loss of the button even though it should pull loose at one or both ends.

The foregoing and other objects of the invention will hereinafter be more fully described and claimed and illustrated in the drawings forming a part of this specification in which like characters of reference indicate corresponding parts in both the views, and in which—

Figure 1 is a perspective view of the cuff portion of a sleeve showing my improvement; Fig. 2 is a sectional view through the cuff, indicating the relation of the button thereto, and Fig. 3 is a detail showing the safety loop in spaced relation to the cuff portions.

The specific form of the attachment may be varied to a considerable extent, and the application thereof to the cuff may be effected in various ways without departing from the spirit of the invention hereinafter specifically claimed.

The drawings illustrate a conventional form of soft shirt cuff 10, a portion 10^a of which is folded back upon the portion 10^b to which the sleeve 11 is secured. These parts of the cuff are provided ordinarily with holes 13 and 13' arranged in pairs, there being two of the holes 13 and 13' in each cuff, and all of the holes, when the cuff is in normal position, being in substantial alinement for the reception of a cuff button B. Ordinarily the cuff button is put in place by passing the base b through all four of the but-

tonholes, beginning with the front or outside hole 13, said base passing thence 55 through the two holes 13' and finally through the inner hole 13. The base of the button is usually smaller than the head for the purpose just stated, and hence there is constant danger of the button dropping 60 from the cuff. In fact, shirts of the type indicated are objected to by many men because of the fear of loss of the buttons. To overcome the objection above referred to I provide a safety loop 14 located between the 65 cuff portions 10^a and 10^b and lying normally between the holes 13 and 13'. The loop may be made of any suitable material and is secured preferably at one end, to the free edge of one of the parts of the cuff, as shown 70 at 15, so that it can lie between the parts of the cuff, either when the parts are folded, as shown in the drawing, or when the part 10^a is folded inward to lie beneath the part 10^b. The loop also is provided with an eye 75 14' formed by elastic material of which the loop is constructed. The eye, therefore, is normally of a size to allow the base b of the button to pass through under force, and then substantially snugly hug the shank b'. 80 It follows, therefore, that even though the button should be put under sufficient strain to cause the base to be withdrawn from place, the button will not be lost because of the engagement between the loop and the 85 shank.

Having thus described my invention, I claim as new and desire to secure by Letters Patent:

The combination with a soft shirt cuff 90 having one part adapted to fold upon the other and said parts having alined cuff buttonholes, of a safety loop of flexible material secured at one end to the free edge of one 95 of the cuff parts and lying between said cuff buttonholes, said loop having an eye in alinement with the cuff buttonholes, said eye being formed and bounded by elastic material adapted to snugly embrace the button shank.

In testimony whereof I have signed my 100 name to this specification in the presence of two subscribing witnesses.

JACOB FALKENBERG.
